CLAIM

The ornamental design for a portable transdermal biomarker sensor device, as shown and described.

DESCRIPTION

FIG. 1 is top-down perspective view of a portable transdermal biomarker sensor device, showing our new design;

FIG. 2 is a front elevation view of the embodiment shown in FIG. 1;

FIG. 3 is a rear elevation view of the embodiment shown in FIG. 1;

FIG. 4 is a left-side elevation view of the embodiment shown in FIG. 1;

FIG. 5 is right-side elevation view of the embodiment shown in FIG. 1;

FIG. 6 is a top-down plan view of the embodiment shown in FIG. 1;

FIG. 7 is a bottom-up plan view of the embodiment shown in FIG. 1;

FIG. 8 is a top-down, front perspective view of the embodiment shown in FIG. 1, illustrating the separate elements thereof in a first configuration, with a top-down, rear perspective view being a mirror thereof;

FIG. 9 is a top-down perspective view of the embodiment shown in FIG. 1, illustrating the separate elements thereof in a second configuration, with a top-down, rear perspective view being a mirror thereof;

FIG. 10 is a top-down, front perspective view of the embodiment shown in FIG. 1, illustrating the separate elements thereof in a third configuration, with a top-down, rear perspective view being a mirror thereof; and,

FIG. 11 is a bottom-up perspective of the embodiment shown in FIG. 1, illustrating the separate elements thereof, with a bottom-up, rear perspective view being a mirror thereof.

The dot-dash lines in the drawings represent the bounds of the claimed design and form no part thereof. The even length broken lines illustrate portions of the portable transdermal biomarker sensor device that form no part of the claimed design.
